[57] CLAIM

The ornamental design of a container for vacuum cleaner accessories, substantially as shown and described.

DESCRIPTION

FIG. 1 is a top, front and right side perspective view of a container for vacuum cleaner accessories showing my new design;

FIG. 2 is a right side elevational view thereof, the vacuum cleaner accessories shown in broken lines are for illustrative purposes only and form no part of the claimed design;

FIG. 3 is a left side elevational view thereof; and

FIG. 4 is a rear elevational view thereof.

FIG. 1

FIG. 2

FIG. 3

FIG. 4
